UNITED STATES PATENT OFFICE.

HENRY E. WEBER, OF CANTON, OHIO, ASSIGNOR TO THE WEBER DENTAL MANUFACTURING COMPANY, OF CANTON, OHIO, A CORPORATION OF OHIO.

DENTAL CHAIR.

1,238,605.

Specification of Letters Patent. Patented Aug. 28, 1917.

Application filed October 30, 1914. Serial No. 869,412.

To all whom it may concern:

Be it known that I, HENRY E. WEBER, a citizen of the United States, residing at Canton, in the county of Stark and State of 5 Ohio, have invented certain new and useful Improvements in Dental Chairs, of which the following is a specification.

The invention relates to adjustable chairs which are adapted to be vertically raised 10 and lowered on the base, the raising and lowering being accomplished by a hydraulic jack. In chairs of this type it is difficult to sustain the chair in a given position of elevation, for the reason that the slightest leakage of the oil or other liquid employed in the lifting jack permits the seat of the chair to subside or drop downward a corresponding distance, and it is practically impossible to make and maintain the valves and pistons 15 of the jack with such closely fitting parts as to prevent a recurrence and continuance of a leakage of the liquid and a corresponding settlement of the chair seat.

The principal objects of the present invention are to provide a quick acting release valve for the liquid in the cylinder of the jack, that will reduce the leakage to a minimum; to provide automatic means for locking and positively sustaining the chair 25 standards when raised to a given position; to provide means for disengaging said locking means immediately in advance of opening the release valve for lowering the chair; and to provide automatic means for gradually closing the release valve to cushion the seating of the sliding standards upon the base and avoiding a shock to the chair seat 30 and its occupant.

These objects of the invention, and ancillary advantages, are attained by the construction, mechanism and arrangement illustrated in the accompanying drawings, forming part hereof, in which—

Figure 1 is a plan view of the extensible 45 standards and base for a dental chair;

Fig. 2, an upright section, generally on line 2—2, Fig. 1, showing the standards partially raised or extended;

Fig. 3, a detached elevation, partly in section, of the releasing and locking devices, as 50 when the standards are raised and locked;

Fig. 4, a similar view, as when the lock is disengaged for opening the release valve;

Fig. 5, a similar view, as when the release valve has been opened;

Fig. 6, a fragmentary section of the release valve;

Fig. 7, a detached plan view of the locking dog; and

Fig. 8, a section of same on line 8—8, 60 Fig. 7.

Similar numerals refer to similar parts throughout the drawings.

The chair base 1, the base standard 2, the locking standard 3, the intermediate standard 4, and the seat standard 5, may be of the general construction and arrangement shown in my Patent No. 958,048, dated May 17, 1910; and the pump 6 with the plunger 7 therein, the cylinder 8 with the piston 9 70 therein, and the intervening check valve 10, for elevating the extensible standards by means of a liquid contained in the base standard, may be of any suitable type or form of such parts employed in a lifting 75 jack of this character, and the details of construction thereof are not necessary parts of the present invention.

The case 11 of the release valve 12 is formed or secured on one side of the base or 80 bottom 13 of the cylinder of the jack and extends radially therefrom to the wall of the base standard, with which, however, it is not connected. The valve 12 is shaped with the conical end 14 adapted to seat in the 85 outer end of the release port 15 communicating with the lower end of the cylinder; and the valve is preferably swiveled in the end of the screw stem 16, as by means of the cylindric head 17 located in the cylindric recess 18 in the forward end of the stem, between which head and the internal rim flange 19 in the end of the stem may be provided the compression spring 20 for normally holding the head of the valve against 95 the stop 21 formed by the inner end of the recess.

The valve and its head are loosely fitted in the surrounding parts of the screw stem, so that the conical end of the valve may have a 100 certain amount of lateral play, thereby enabling it to truly find its seat when it is

closed by being moved toward and into the outer end of the release port. By thus loosely swiveling the conical valve in the end of its stem, the same cannot only truly find 5 its seat, but will not be rotated therein by the turning of the screw stem for opening and closing the valve, thereby preventing undue friction and wear, while the spring 20 serves to surely withdraw the valve from 10 its seat to open the port when the stem is screwed outward therefrom.

The stem 16 is provided with the steep thread 22 operating in the corresponding groove 23 provided in the case, for moving 15 the valve to and from the release port by a rotation of the stem; and on the outer end of the stem is secured the pinion 24 meshing with the rack 25 secured on the lower end of the upright actuating rod 26, by the vertical 20 movements of which the valve is opened and closed. The valve case is preferably made with the guide 27 for the rack, the bearing 28 for the outer end of the valve stem, and the recess 29 for receiving the pinion and 25 permitting a lateral movement thereof with the endwise movement of the stem, during which movement the teeth of the pinion slide laterally upon the teeth of the rack.

The rack 25 is provided with the tubular 30 stem 25' having the lower cylindric socket 30 therein for the compression spring 31, and the larger upper cylindric socket 32 therein for the head 33 on the sliding shank 34 on the lower end of the actuating rod 35 26, below which head the centering pin 35 may extend downward into the compression spring.

By a compression of the spring 31, the 40 head 33 on the sliding shank may rest on the stop 36 formed at the lower end of the upper cylindric socket, and the bushing 37 is adjustably secured, as by screwing, therein; the lower end of which bushing forms the stop 38 for the head to limit the upward 45 sliding movement of the same; which bushing may be fixed in any desired position of adjustment by the lock nut 39. By this construction and arrangement, the actuating rod and the rack on its lower end, may 50 be slightly extended with reference to each other, within the extent of positive stops in each direction, and the compression spring serves to hold the same in extended 55 relation to the extent of the strength of the spring.

The actuating rod 26 for the release valve is slidably mounted in upright position in the guide bearings 40 and 40' formed or provided in the lugs 41 and 41' formed or 60 secured on the inner side of the wall of the base standard; and the upper bearing 40' may be in the form of an adjustable bushing, as shown; between which bushing and the shoulder 42, formed on the rod above

the lower bearing 40, is provided the controlling compression spring 43 located around the reduced upper end portion 26' of the rod, which spring serves to normally hold the actuating rod downward to rotate and hold the release valve in closed position, with the expansion spring 30 compressed, and the head of the sliding stem, stopped on the shoulder 36 in the tubular stem of the rack, as shown in Fig. 3, which is the normal position of the parts when the 75 release valve is closed.

The locking dog 44 is mounted by the pivot 45, adjacent to the upper end of the actuating rod 26, in the bracket 46 formed or secured on the upper end of the base 80 standard 2; which dog is provided with a plurality of cam teeth 47, 47' and 47'' on its free end adapted to engage and bite into the adjacent face 48 of the intermediate standard 4 for clamping and locking the 85 same by a wedging cam action to prevent the said standard from dropping or moving downward with respect to the base standard when elevated therein and engaged by the cam teeth of the dog. 90

The second or intermediate tooth 47' is located farther than the first or lower tooth 47 from the axis of the pivotal bearing of the dog, and likewise the third or upper tooth 47'' is located a little farther than the 95 intermediate tooth from the axis of the pivotal tooth, and the intermediate tooth protrudes slightly beyond the plane of the first and third teeth; so that the gripping effect of each one of the second and third teeth is greater than the previous one brought into play. To designate the difference in the distance of the several teeth from the pivotal axis of the cam dog, they are referred to herein as differential teeth. 100

The parts are so constructed and arranged that the first or lower cam tooth 47 on the end of the dog normally rests in wedging engagement with the face 48 of the intermediate standard by the weight of the dog, which may be supplemented by the action of one or more springs 49 located in the sockets 50, and abutment pins 51 having their inner ends sliding endwise in the sockets and their outer ends in sliding contact with the stop face 52 provided in the supporting bracket of the dog; and the pendent foot 53 is provided on the dog in the path of the head 54 secured on the upper end of the actuating rod 26, by the upward movement of which head the dog is adapted to be lifted and rotated upon its pivot to move the cam teeth free from the adjacent face of the intermediate standard, as shown in Figs. 4 and 5. When, however, the actuating rod is held downward by its controlling spring 43 in its position for closing the release valve, the head 54 on its upper end is 110 115 120 125

located at a slight interval below the foot 53 of the locking dog, so that the cam teeth thereof may drop and rotate downward into wedging engagement with the adjacent 5 face of the intermediate standard.

The usual release lever 55 is fulcrumed on the pivot 56 mounted in the wall of the base standard, which lever is provided with the pedal 57 on its outer end, and the arm 10 58 on its inner end engaging under the cross pin 59 on the actuating rod, by means of which this rod may be operated upward against the action of the controlling spring 43, by the operator's foot upon the pedal; 15 and the usual pump lever 60 is fulcrumed on the pivot 61 also mounted in the wall of the base standard, which lever is provided with a suitable pedal 62 on its outer end and the arms 63 on its inner end 20 engaging over the oscillating fingers 64 pivoted to the stem 65 of the pump plunger 7, by means of which the plunger is operated downward against the action of the controlling spring 66, for raising or elevating the 25 chair standards by pumping the liquid into the cylinder of the lifting jack, all in a manner well known in the art.

The step 67 is formed or secured on the stem 25' of the rack, as by means of the 30 collar 68 secured between the bushings 69 and 69' screwed on the stem; which step is positioned in the path of the abutment pin 70 slidingly mounted in the bore 71 in the lower end of the intermediate standard, 35 wherein it is held upward by the stop screw 72, and is cushioned against upward movement by the compression spring 73 in the bore; and these parts are so arranged that the release valve will be automatically 40 closed by the spring cushioned contact of the pin against the step as the intermediate standard approaches its seat upon the base standard when dropped or moved downward therein, thereby preventing a shock or jar 45 when these several standards are finally stopped at the end of the downward movement.

The lug 74 is provided on the lower end of the intermediate standard in the path of the head 54 on the actuating rod 26, by means 50 of which the release valve is gradually opened as the intermediate standard approaches the end of its proper upward movement, thereby preventing an elevation of the standards beyond the extent of their respective guides.

In the operation of the chair it is evident that the controlling spring 43 will normally hold the release valve actuating rod downward for holding the valve closed, as shown 55 in Figs. 2 and 3; in which relation of the parts the foot 53 of the locking dog is not supported by the head on the actuating rod, and the first cam tooth of the dog rests in wedging engagement against the face 48 of

the intermediate standard. Whenever the 65 standards are extended upward by an operation of the pump, it is evident that the intermediate standard is free to slide upward along the tooth of the locking dog, which rests against it, and the relation of 70 these parts remain in the position shown in Figs. 2 and 3 as long as there is no leakage from the cylinder through the release valve, or otherwise, to permit a downward movement or dropping of the standards. 75

It is evident, however, that should there be such a leakage, the cam action of the first tooth 47 will bite into the adjacent face of the intermediate standard, and if the downward movement continues far enough, the 80 second tooth 47' of the dog will impinge said face, by a wedging cam action, whereby the intermediate standard is rigidly clamped between the locking dog and the opposing 85 guides of the base standard, so that the intermediate standard will be stopped against any further downward movement and will be held rigidly against any lateral movement with respect to the base standard.

Should there be a considerable looseness 90 between the guides of the standards, the upper or third cam tooth on the locking dog might be brought into play, but it has been found in practice that the clamping range 95 of the second tooth is usually sufficient to clamp and lock the intermediate standard to the base standard.

In event the second or third tooth shall have been brought into play, or the first tooth shall be so engaged by the abutting 100 face of the intermediate standard as to prevent a disengagement of the same by an elevation of the actuating rod of the release valve, it is only necessary to slightly elevate 10 the standards by a single depression of the pump lever, whereupon the locking dog is raised into the position where its lower tooth merely rests against the face of the intermediate standard, as shown in Fig. 3.

When the parts are in this relation, and it 110 is desired to drop the extended standards downward, the foot of the operator is applied to the pedal of the release lever, and a depression of the same serves to elevate the actuating rod of the release valve. It 115 is evident, however, that the rack 25 on the lower end of the actuating rod will not be raised by the first portion of this movement because of the extensible connection between the rack and the rod, until the head 33 has impinged the lower end of the bushing 38, as shown in Fig. 4; during which initial movement of the actuating rod, the head 54 thereon impinges the foot of the locking dog and the teeth therefore are 120 swung free of the adjacent locking face 48 of the intermediate standard, as shown in Fig. 4, and during this initial movement of

the actuating rod, the release valve remains closed.

5 A further elevation of the actuating rod, however, carries with it the rack on its lower end into the position shown in Fig. 5, thereby rotating the release valve in the direction to withdraw its conical end from its seat in the release port, as shown in Fig. 6, thereby permitting an escape of the liquid 10 from the cylinder of the jack, which permits the extended standards to drop downward; and it is evident that the same further raising of the actuating rod lifts the locking dog and rotates the cam teeth there- 15 of entirely away from the locking face of the intermediate standard, as shown in Fig. 5.

I claim:

20 1. A chair base including a base standard and one or more extensible standards, and a wedging dog having differential teeth mounted on one standard with one tooth normally resting against another standard for locking the same against downward 25 movement.

30 2. A chair base including a base standard and one or more extensible standards, and a cam dog having differential teeth pivoted on one standard with one tooth normally resting against another standard for locking the same against downward movement.

35 3. A chair base including a base standard and one or more extensible standards, a wedging dog having differential teeth mounted on one standard with one tooth normally resting against another standard for locking the same against downward movement, and means for moving the dog on the one standard for disengaging it from 40 the other standard.

45 4. A chair base including a base standard and one or more extensible standards, a cam dog having differential teeth pivoted on one standard with one tooth normally resting against another standard for locking the same against downward movement, and means for rotating the dog on the one standard for disengaging it from the other standard.

50 5. A chair base including a base standard and one or more extensible standards, a wedging dog having differential teeth mounted on one standard with one tooth normally resting against another standard 55 for locking the same against downward movement, a lifting jack in the base standard, and releasing means for the jack acting to disengage the wedging dog before releasing the jack.

60 6. A chair base including a base standard and one or more extensible standards, a wedging dog mounted on one standard normally resting against another standard for locking the same against downward move-

ment, a lifting jack in the base standard, 65 and an extensible actuating rod for releasing the jack arranged to disengage the wedging dog by its extension and to release the jack when extended.

7. A chair base including a base standard 70 and one or more extensible standards normally seated in the base, a lifting jack in the base standard, an actuating rod for releasing the jack having a step thereon, and a spring-cushioned pin on one of the extensible standards in the path of the step for gradually stopping the jack as said extensible standard approaches its seat in the base. 75

8. A chair base including a base standard and one or more extensible standards, a hydraulic jack for extending the standards, and releasing means for the jack including a screw stem having a valve swiveled at one end. 80

9. A chair base including a base standard 85 and one or more extensible standards, a hydraulic jack for extending the standards, and releasing means for the jack including a screw stem having a valve loosely swiveled 90 at one end.

10. A chair base including a base standard and one or more extensible standards, a hydraulic jack for extending the standards and having a release port, and releasing means for the jack including a screw stem 95 having a valve swiveled at one end, said valve having a conical end adapted to seat in the opening of the port.

11. A chair base including a base standard and one or more extensible standards, a hydraulic jack for extending the standards and having a release port, and releasing means for the jack including a screw stem having a valve loosely swiveled in its end, 105 said valve having a conical end adapted to seat in the opening of the port.

12. A chair base including a base standard and one or more extensible standards, a hydraulic jack for extending the standards, releasing means for the jack including a screw stem having a valve swiveled at one 110 end and a pinion on the other end, and an actuating rack engaged with the pinion.

13. A chair base including a base standard and one or more extensible standards, means for locking the standards together, a hydraulic jack for extending the standards, releasing means for the jack including a screw stem having a valve on one end and a pinion on the other end, and an actuating rod having a rack extensibly connected therewith engaging with the pinion for initially disengaging the lock and subsequently opening the valve. 115

14. A chair base including a base standard and one or more extensible standards, a wedging dog having differential teeth mounted on one standard with one tooth 120

normally resting against another standard for locking the same against downward movement, and spring means bearing on one standard for pressing the dog against another standard.

15. A chair base including a base standard and one or more extensive standards, a hydraulic jack including a screw stem hav-

ing a valve loosely swiveled at one end, with yielding means for holding the valve in normal position. 10
